UNITED STATES PATENT OFFICE.

JESSE OPPENHEIM, OF NEW YORK, N. Y., ASSIGNOR TO HYMAN & OPPENHEIM, OF NEW YORK, N. Y., A CORPORATION OF NEW YORK.

HAIR-PIECE ATTACHMENT.

Application filed February 16, 1927. Serial No. 168,592.

This invention relates to hair dressing appliances and has particular reference to devices employed for the attachment of hair pieces to bobbed hair as now commonly worn so that the wearer of my improved device will present, for dress or other purposes, the appearance of having long hair which may be dressed or manipulated in any desired style.

Among the objects, therefore, of the invention is to provide an attachment means that may be applied easily and hold securely to bobbed hair even of the shortest nature such as the back of a bovish bob, and which likewise with equal facility may be readily removed when so desired.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a general or perspective view of one embodiment of my invention.

Fig. 2 is a plan view indicating the manner of self-holding attachment to bobbed hair.

Fig. 3 is an inside face view of a modification.

Fig. 4 is a vertical transverse sectional detail showing the relation of the gripping member to the short hair.

Referring now more specifically to the drawings, I indicate my improved attachment means as comprising a gripping member in the form of a closely coiled contractile spring 10, the end loops or coils 11 of which are bent at right angles to the main coils of the spring for ready attachment as by stitching at 12 to the ends or points of any suitable size, form, or construction of bases or mats 13, each of which carries or has interwoven therewith in any well known or suitable manner a strand or switch of hair 14. The stitching or tacking at 12 will of course be understood as being of ample strength for the purpose of manipulation of the attachment means.

With the switches 14 in normal open or pendent form, each hanging from its base

13, the operator will grasp with the thumb and finger of the respective hands, the bases 13, and assuming that she wishes to apply the attachment to her back hair, will reach with the device held as stated, bringing the attachment directly over or against that portion of the hair to which it is to be attached. She will then draw her hands apart, putting the spring 10 under stretch with the result that the several coils of the spring will be spaced laterally from one another, leaving a gap or space between each two adjacent coils, into which a number of fibers or hairs of her own natural hair will be received, the edges of the respective coils adjacent to her head entering freely into or between the hairs of her head like a comb. The device for this purpose is given a slight downward sweep through say a half inch to an inch to facilitate the reception of the hair between the coils as stated. This result obtains irrespective of the length of her hair for even though it may be only a half inch or more in length, the hair nevertheless will be received between the coils of the spring, and when she releases the strain on the ends of the spring, the normal tendency for the spring to contract will function and so all the hair located between the several coils of the spring will be securely gripped, making a reliable connection between the attachment and her natural hair. This result is not accompanied in any manner with discomfort to the wearer, and the natural gripping tension of the spring is increased by the fact that the hair received within the spring or between its several coils has the effect of increasing the natural tension of the spring.

After the device is thus attached to her natural hair, an act that is performed as quickly as the application of an ordinary back comb to a woman's hair, the switches 14 may be dressed so as to form a coiffure of any suitable form or arrangement according to the style or wishes of the individual, the amount of hair involved in the switches, or the like. Also the character of the side portions of her natural hair will influence the manner of dressing the attachment hair.

Any suitable stay means may be provided extending between the bases 13 to prevent overstretch or strain on the gripping member or spring 10. This is indicated at 15 in the form of a tape of flexible but non-elastic

construction strongly stitched or otherwise attached to the base members 13 and preferably outside of the spring so as not to interfere with the admission of the natural hair between the adjacent coils of the spring as above explained.

The form of the invention shown in Fig. 3 is one in which the auxiliary hair, in whatever form it may be utilized, such as clusters, curls, bangs, or the like, is shown supported upon a woven or textile supporting means which may be thought of as a foundation and to two spaced points of which the end coils 11 of the gripping member 10 are tacked or otherwise secured. The selection of the points of attachment is such that when the gripping member is in normal contracted position, that portion of the foundation 15^a between the points of attachment is loose or slightly baggy. As before explained, however, the foundation being flexible and non-elastic constitutes a stay preventing overstrain on the gripping member at the time it is being applied.

Fig. 4 indicates the relation of the short hair of the wearer's head to the gripping member, but with the auxiliary hair suspended loosely from the gripping member.

I claim:

1. The herein described hair piece for the dressing of bobbed hair comprising a gripping device in the nature of a closely coiled spiral spring, means attached to the ends of the spring for stretching it to enable the

individual coils thereof to enter the natural hair like a comb, and a mass of auxiliary hair carried by the stretching means aforesaid. 35

2. The herein described hair piece for attachment to short bobbed hair, the hair piece comprising a foundation carrying a strand or mass of auxiliary hair, and resilient short hair gripping means having both its ends attached to said foundation, the gripping means being so constructed as to automatically grip the short hair when the ends of the gripping means are drawn apart and then released. 40 45

3. In a hair piece attachment of the character set forth, the combination of a hair gripping member, auxiliary hair, supporting means for the auxiliary hair connected to the gripping member and so arranged that when force is applied thereto the gripping member will open to receive the short hair 50 and when the force is reduced the gripping means will automatically grip and hold upon the natural short hair, leaving the auxiliary hair free to be arranged or dressed thereover. 55 60

4. Mechanism as set forth in the preceding claim in which the supporting means for the auxiliary hair constitutes a member to prevent overstrain upon the gripping member when being applied. 65

In testimony whereof I affix my signature.

JESSE OPPENHEIM.
